UNITED STATES PATENT OFFICE.

ABRAHAM L. ADAMS, OF BRIDGEPORT, CONNECTICUT.

MACHINE FOR WINDING AND CUTTING CLOTH ROLLS.

No. 878,705.

Specification of Letters Patent.

Patented Feb. 11, 1908.

Application filed January 10, 1907. Serial No. 351,680.

To all whom it may concern:

Be it known that I, ABRAHAM L. ADAMS, a citizen of the United States, and a resident of Bridgeport, in the county of Fairfield and State of Connecticut, have invented certain new and useful Improvements in a Machine for Winding and Cutting Cloth Rolls, of which the following is a specification.

My invention relates to a machine for forming or winding rolls from wide strips of cloth and cutting said rolls up into spools of any desired width and of a diameter equal to the original roll.

To enable others to understand my invention, reference is had to the accompanying drawings, in which—

Figure 1 represents a broken front elevation of the machine; Fig. 2 is a vertical sectional view of the cloth roll winding mechanism on line 2 of Fig. 1; Fig. 3 is a vertical sectional view of the spool forming mechanism on line 3 of Fig. 1; Fig. 4 is a broken view of a portion of the spool cutting mechanism; Fig. 5 is a broken view partly in section of the spool cutting mechanism on line 5 of Fig. 4; Fig. 6 is a broken detail view partly in section of the cloth winding arbor and its accompanying paper tube mounted thereon; Fig. 7 is an enlarged front elevation of the cloth roll chuck and sectional view of its arbor; Fig. 8 is an enlarged detail sectional view of the cloth roll chuck on line 8 of Fig. 7; broken sectional view of a roll of cloth engaged by the chuck and broken view of its arbor; Fig. 9 is an enlarged detail side elevation of the driver or key adapted to connect with and drive the paper tube mounted on the cloth winding arbor; Fig. 10 is an enlarged broken sectional view of the cloth winding arbor and the paper tube or core on which the cloth is directly wound, showing the manner of connecting the tube with the arbor; Fig. 11 is a similar view of the cloth winding arbor and paper tube in proper position for winding; Fig. 12 is an enlarged detail side elevation of the weighted lever for the cloth feed rolls; sectional view of said rolls and one of the cross rods of the machine; Fig. 13 is a broken view of the machine bed, lower presser roller and levers therefor; Fig. 14 is an enlarged broken detail view of the cloth roll holding chuck.

1 represents the bed of the machine and 2 the legs.

55 The mechanism for first winding the cloth into long rolls preparatory to cutting up said

rolls into spools, is as follows: Referring to Figs. 1 and 2, 3 and 4 are standards mounted on the bed 1. 5 and 6 are tie-rods connecting the standards, and they also serve as 60 tension rods for the cloth strip 7 from which the roll 8 is formed; the cloth first passing through the tension rods 9 mounted on the bed. 10 and 11 are combined pressure and cloth feed rolls journaled in the outer ends of 65 the arms 12 and 13, which arms are secured to the upper shaft 14. These rolls are driven from the short shaft 15, carrying the tight and loose pulleys 16 and 17. 18 is a double pulley carrying the belt 19 from 70 shaft 15 to the idle pulley 20 on shaft 14, and from thence to the pulley 21 on the upper feed roll 10. On the opposite end of this roll is the pinion 22 meshing with the pinion 23 on the lower feed roll 11 for driving said 75 lower roll. The cloth 7, after leaving the rod 5, passes between the combined pressure and feed rolls 10 and 11, and from thence to the winding arbor 24 about which its end is secured preparatory to winding. The winding arbor is independently driven through the medium of the pulleys 18, 25 and belt 26. The pulley 25 is mounted on the shaft 27 journaled in the short standard 28, and it carries on its inner end the pinion 29 meshing 80 with the intermediate gear 30, which gear meshes with the pinion 31 on the winding arbor.

To facilitate the removal of the cloth tension rolls from the winding arbor, and also to 90 form a core to support the spools when cut from the cloth rolls, the paper tube 32, which tube is the full length of the proposed cloth rolls, is slipped on to the winding arbor and is made to rotate in unison therewith and 95 not slip, as follows: 24^a (Fig. 10) is a keyway running throughout the length of the winding arbor, and 24^b is an incline extending from the journal end 24^c of the arbor to the bottom of the keyway. 33 (Fig. 9) is a 100 driver having the sharp pointed pins 34 projecting from its upper surface. The paper tube is extended over the journal end of the arbor, as shown at Fig. 10, and the driver 33 inserted with its forward beveled end against 105 the bevel 24^b of the arbor. End pressure on the driver will elevate its forward end into the keyway and force the pins 34 through the paper tube to hold it against rotation on the arbor and also furnish means for attaching 110 the cloth to the tube. When the driver is well seated, the paper tube is forced back as

shown at Figs. 6 and 11, which operation will complete the engagement of the pins 34 with the paper tube. A standard similar to 28, but not shown, supports the opposite end 5 of the winding arbor. 35 and 36 are collars brought against the ends of the paper tube and are secured in this position by their set screws 37, one of which is seen more clearly at Fig. 11, engaging with the bottom of the 10 keyway in the winding arbor. These collars are larger in diameter than the paper tube to protect the pins and support the weight of the combined pressure and cloth feed rolls 10 and 11 during the initial formation of the 15 cloth roll on the winding arbor. When, therefore, the diameter of the cloth roll has increased in dimensions larger than the diameter of these collars, the grip of the cloth roll on the paper tube of the winding 20 arbor will be firm enough to enable said cloth roll to sustain the entire weight of the pressure rolls 10 and 11. The roll 11 remaining directly in contact with the cloth roll during the formation of the latter. As 25 the cloth roll increases in size the arms 12 and 13 will be elevated by the contact of the cloth roll with the pressure roll 11.

38 and 39 are levers pivotally supported to the arms 12 and 13 and carrying at their free 30 ends weights 40 and 41, one of said levers and weights being shown more clearly at Fig. 2. These levers rest on the boxes or end bearings of the upper roll 10, and the weights are adjustable on said levers so as to impart a 35 greater or less pressure on the cloth roll while it is being wound. In winding long cloth rolls to be afterwards cut up into narrow spools, it is of the utmost importance that the cloth roll should be of uniform diameter and density throughout its entire length 40 in order that the spools cut therefrom may also be uniform. If, therefore, the cloth roll tends to increase in diameter on one end more than on the other, it will produce 45 puckers in the cloth. This tendency is checked by means of the before-mentioned weights and levers, which weights are shifted to suit the condition of the cloth roll, and, at times, it may be necessary to temporarily remove 50 one of the weights altogether until conditions are favorable for its replacement.

To insure compact and even winding of the cloth roll intermediate of its ends, the weight 43 is added as shown at Figs. 1 and 12. This 55 weight is attached to one end of the lever 44, while the opposite end bears against the underside of the shaft 14 and is slidably secured thereto so that the lever can be shifted and its weight brought to bear at any point between the ends of the cloth roll. When not 60 required, the weight can be placed on top of the lever as shown in dotted position at Fig. 12.

The cloth roll is supported on its underside 65 by the presser roller 45 (Figs. 2 and 13),

which roll is journaled on the lever 46, which, in turn, is hinged to the plate 47 secured to the bed 1. This presser roll is actuated to bear against the bottom of the cloth roll and is kept in contact therewith during the entire 70 formation of said cloth roll as follows: 48 is a weighted lever fulcrumed on the screw 49, and 50 is a rod connecting one end of said lever with the lever 46, while the opposite end of lever 48 carries the adjustable weight 75 51. When the presser roll 45 is not in use, the weighted end of the lever 48 is raised to depress said roll and a pin is inserted in the hole 52 of the bracket 53 so as to contact with the upper edge of the lever 48. 80

When a cloth roll has been wound to the diameter required, the cloth connection therewith is severed and the winding arbor lifted from its bearings and the paper tube on which the cloth roll is wound is removed 85 from the arbor, and said arbor replaced in its bearings to repeat the operation of winding another roll in the manner previously described. The finished roll, together with its paper tube core, is slipped on to the arbor 90 54 of the spool cutting end of the machine. This arbor is journaled in the standard 55 and arm 56. The former rests on the bed 1, and the latter is removably secured on the projecting ends of the rocker shaft 57 journaled in the standards 55 and 58; and the rod 59 also resting in said standards. 95

60 (Figs. 1, 7, 8 and 14) is the cloth roll holding chuck slidably mounted on the arbor 100 54 and rotatably driven thereby. The longitudinal movement of the chuck is effected through the medium of the arm 61 whose upper end is journaled in the hub 60^a of the chuck, and the lower end is provided with the hubs 61^a and 61^b, having holes 105 therethrough and mounted to slide on the rods 59 and 62 and also on the rocker shaft 57. This double support of the arm 61 will insure its being moved along said rods without cramping or sticking so that the chuck 110 may be moved longitudinally on the arbor 54 smoothly and evenly without halting or jumping for the purpose presently to be more fully described. As the spools are severed from the outer and free end of the 115 cloth roll, or, in other words, from the end opposite to that engaged by the chuck, it is necessary that the chuck hold and drive the cloth roll without distorting in the least the cylindrical appearance of the cloth roll during 120 the operation of spooling.

Referring to Figs. 7 and 14, 62^a are radially disposed sharp-pointed pins projecting from the front face of the chuck, and centrally located between each row or series of these 125 pins are the slides 63 operatively mounted in the radially disposed slots 64, one of which slots being clearly shown at Fig. 14. 65 are screws whose threaded ends enter threaded holes in said slides whereby they can be held 130

firmly to the chuck. The rear face of the chuck 60 is provided with elongated holes (not shown) whereby said screws can be moved toward or away from the center of the chuck, and the pins 66 carried by these movable slides are inclined or pitched to one side and downward for the purpose presently to be described. 67 and 68 are two short slides operatively mounted in slots of the chuck 10 similar to the slots for the longer slides just described. These slides carry the angular pins 69 and 70 adapted to be forced into the outer surface of the cloth roll and are held in said position by the set screws 71.

15 When the cloth roll is mounted on the arbor 54 of the spooling mechanism, it is brought against the front face of the chuck 60 with force sufficient to cause the pins 62^a and 66 to embed themselves into the end of the roll, when the slides carrying the pins 66 are drawn out, then said slides are forced down their full distance and locked by the screws 65 as before mentioned. The pins 66, as before stated, are inclined in two directions, viz.: downward and to one side in the direction that the chuck rotates as shown by the arrow *a* (Figs. 3 and 7). This inclination of the pins imparts to them a claw like effect which serves to retain the cloth roll 20 firmly against the face plate. Then the slides 67 and 68 are brought down to force the angular pins 69 into the outer cylindrical surface of the cloth roll so as to provide an additional holding power.

30 The arbor 54 is rotated from the short shaft 72 (Fig. 1) carrying the tight and loose pulleys 73 and 74, which shaft is rotated from any convenient source. From the double pulley 75, on said shaft, the belt 76 conveys the power to the large pulley 77 on the outer end of the arbor 54. 78 is a 35 smaller pulley integral with the larger pulley which carries the belt 79 around a groove of the small double pulley 80 journaled on the outer end of the rocker shaft 57. The other groove of this double pulley carries the belt 81 around the pulley 82 mounted on the cutter shaft 83, shown more clearly at Fig. 3. This cutter shaft is journaled by one of its 40 ends in the projecting end of an arm whose hub portion 84 is secured to the rocker shaft 57, seen more clearly at Fig. 1. The other end, back of the rotary cutter 85, is journaled in the arm 86 (see Fig. 3) of the handle lever 45 87 secured to the rocker shaft 57.

The mechanism for advancing the cloth roll into the cutting field is as follows: Referring to Figs. 1, 3, and 4, 88 and 89 are pulleys rotatably mounted on the pins 90 and 50 91 projecting from the cross bars 92 and 93 secured to the rods 59 and 62. 94 is a thin metal strip, having teeth on its outer edge, a band saw being used, drawn tightly around these pulleys with their free ends anchored 55 firmly in the block 95 secured to the chuck

carrying arm 61. The rear face of these pulleys have a slight flange against which the back or toothless edge of the metal strip runs and is maintained thereagainst by the rollers 96 and 97. 98 and 99 are pulleys rotatably mounted on the studs 100 and 101, which studs are adjustably mounted on the rod 62. 102 is a thin metal band passing around these pulleys whose free ends, together with the toothed feed band 94, is secured in the clamp 75 103. The band 102 is also secured to the lower end or rear projection 61^c of the chuck carrying arm 61 by the screw 104, as shown more clearly at Fig. 5. The proper tension is maintained on the bands by means of the 80 set screws 105 and 106 engaging with the uprights 55 and 107, shown more clearly at Figs. 1 and 4. 108 is a support frictionally mounted on the rocker shaft 57 and carrying at its upper end the measuring scale 109. 85 110 is an arm journaled on the pin 90, seen at Fig. 1, and it carries at its lower end the pawl 111 adapted to engage the teeth of the feed band 94. 112 is stop pin projecting from the bed of the machine and carrying the 90 short pin 112^a at right angles thereto, and 113 is an arm mounted on the hub of the arm 110 and is secured thereto by the thumb screw 114.

Setting the machine to cut off spools from the cloth roll of the exact width desired, is as follows: The thumb screw 114 is first turned back so as to leave the arm 113 free on the hub of the arm 110 and said arm 113 is then brought against the pin 112, then the pawl 111 is thrown out and the arm 110 is allowed to drop against the pin 112^a, and the chuck 60 is moved forward by means of the arm 61 until the end of the cloth roll has projected far enough into the cutting field to trim off the uneven or ragged end of the roll whereupon the lever 87 is pressed downward to bring the rotary knife or cutter 85 into action for the trimming process, after which operation the cutter is allowed to drop into its 110 normal position on the projection 115 rising from the bed, as shown at Fig. 3.

Having previously determined the width of spools to be cut from the cloth roll which, let it be supposed is one inch, then the scale 115 109 is brought up on a line with the outer circumferential face of the cloth roll; the pawl 111 thrown into engagement with the teeth of the feed band 94 and is operatively held in such engagement by its spring 116, 120 whereupon the arm 110 is swung on its support and to the left a distance which will represent an inch movement forward of the cloth roll. This distance is determined as follows: The pitch of the feed band teeth 125 represent the subdivisions of the scale; for instance, if the pitch is one-sixteenth of an inch, and the width of the spools are to be one inch, then the operator has simply to count sixteen clicks as the pawl is being 130

drawn back over the teeth of the feed band, and when the pawl has passed over these number of teeth, the arm 113 is firmly clamped to the hub of the arm 110, and when 5 this latter arm is brought against the pin 112^a, the pulleys 88 and 89 will be rotated by the engagement of the pawl with the feed band teeth and the arm 61 will be moved forward one inch and the cutter brought up 10 to sever a spool of one inch in width from the end of the cloth roll. When the arm 110 is thus brought against its stop, the arm 113 will be carried to the right and away from the stop pin 112, as shown at Fig. 4, so that in moving 15 the arm 61 forward to cut another spool of the same width as before, the arm 110 is simply moved back until the arm 113 engages the pin 112, which engagement will represent the proper distance that the arm 20 110 is to be moved back to cut the proper width of spool. It will, of course, be understood that the arms 110 and 113 can be set to cut any width of spool required. The right hand end of the scale being directly in 25 line with the cutting edge of knife, the operator can readily see if the forward end of the cloth roll stands in proper relation with the mark on the scale which is to determine the width of the spools to be cut, and thus easily 30 and quickly adjust the position of the arms 110 and 113 in case they have accidentally become disarranged or changed in relation to each other, and thus avoid spoiling the spools.

35 While the machine is in operation, the cutter 85 is kept in rotative action in the manner previously described. To cut the cloth roll so as to maintain a uniform width from the circumference of the spool to the center, and also to keep the faces or sides of the spools smooth and even, it is necessary to keep the edge of the cutter in proper form. To give the best results, the cutter should have what is called a "wire edge". To accomplish this so as to keep the cutter in perfect order for each cutting, the emery wheel 117 is kept in constant touch with the rotating cutter while such cutter is in its normal rearward position. The engagement of the 45 emery wheel will be only just sufficient to maintain the proper cutting edge.

118 (Fig. 3) is the standard in whose upper end the emery wheel is journaled, while its foot 118^a is journaled in the ears 119 of the 50 base plate 120. 121 is a small shaft carrying the pulley 122, and 123 is a belt leading therefrom to the pulley 124 on the emery wheel arbor 125 for driving said wheel. The belt 126 (see also Fig. 1) leads from the 55 double pulley 75 to a pulley (not shown) on shaft 121 for driving said shaft. The standard 118 is adapted to be tilted so as to bring the corner of the emery wheel in contact with the cutter by means of thumb screws in 60

the foot whose ends contact with the base 65 120. One of these screws 127 is shown at Fig. 3. To maintain a feather edge on the cutter, the round emery stick 128 is allowed to bear lightly against the face of the cutter opposite the emery wheel 117. 129 is a 70 standard for this emery stick.

130 (Fig. 1) is a lead ring on the arbor to protect the edge of the rotary cutter 85 when said cutter has severed a spool from the cloth and a section from the paper tube. 75 131 is an adjustable stop screw mounted on the handle lever of 87 to engage with the upright 107 and limit the upward movement of said rotary cutter. 132 (Figs. 1 and 4) is an adjustable stop screw carried by the 80 chuck carrying arm 61 to prevent carrying the chuck into the cutting field.

As before mentioned, the cloth 7 (Figs. 1 and 2) is drawn through the rolls 10 and 11 and wound about the arbor 24 into a long 85 roll of any desired diameter. As the rolls 10 and 11 always travel at a uniform rate of speed, the pull on the cloth strip would increase as the diameter of the roll increased, which would result in unduly stretching and 90 distorting the cloth. This would be particularly objectionable with cloth cut on the bias. To obviate this differential travel, the pulley 25 (Fig. 1) is frictionally mounted on its shaft so that the pressure of the rolls 10 95 and 11 will control the frictional drive of the pulley 25 and thus reduce the travel of the winding arbor proportionate to the delivery of the rolls 10 and 11.

As will be observed, by referring to arrows 100 a, Fig. 3, that the cutter 85 and the cloth roll 8 rotate in the same direction. This feature is absolutely essential in cutting sections from a roll of cloth, especially when the cloth roll and cutter are of the same diameter. If they rotated in the opposite direction, the two circumferences would simply 105 roll together and produce no cutting effect. In cutting a single strip of cloth, the cutters must rotate in the opposite direction with 110 their cutting edges lapped to give a shearing cut, but when a circular cutter is used in cutting transversely through a cloth roll, the roll and cutter must rotate in the same direction.

115 While I show and describe the slides 63 as carrying angularly disposed or hook-shaped pins, I hold myself at liberty to insert such hook-shaped pins in the face of the chuck and not in the slides, or in both slides and chuck.

Having thus described my invention, what I claim as new and desire to secure by Letters Patent is:—

1. In a machine of the character described, 125 a rotatable winding arbor adapted to support a paper tube about which cloth is wound, and a removable prong carrying driver

adapted to engage the tube and thus cause the same to rotate with said arbor, for the purpose set forth.

2. In a machine of the character described, a rotatable winding arbor adapted to support a paper tube to form the core for a cloth roll, means for rotating said tube and arbor together, combined feed and pressure rollers through which the cloth is fed, detachable weights for said rollers, one of said rollers adapted to engage the cloth roll as it is being formed and by means of the weights distribute the pressure thereon so as to secure uniform and even winding, for the purpose set forth.

3. In a machine of the character described, a rotatable winding arbor adapted to support a paper tube about which cloth is wound into a roll and to form a core therefor, means for temporarily securing the tube to the arbor, combined feed and pressure rollers through which the cloth is fed, detachable weights for said rollers adapted to distribute the pressure on the cloth roll so as to insure even winding of the same, means for rotating said feed and pressure rollers, for the purpose set forth.

4. In a machine of the character described, a rotatable winding arbor, adapted to support a paper tube about which cloth is wound into a roll and to form a core therefor, means for temporarily securing the tube to the arbor, arms, a support therefor, the free ends of said arms adapted to move through an arc of a circle, combined feed and pressure rollers journaled in bearings located in the free ends of said arms, means for rotating said rollers, one of said rollers adapted to bear against the cloth roll during the winding operation, detachable weights adapted to exert a pressure at the ends of said rollers, an intermediate detachable and shifting weight adapted to contact with the upper one of said rollers, a pressure roller adapted to engage the lower surface of the cloth roll during the winding of the same, for the purpose set forth.

5. In a machine of the character described, a rotatable winding arbor adapted to support a paper tube about which cloth is wound into a roll and to form a core therefor, said arbor having a key way therein, a removable prong carrying driver adapted to engage the tube and thus cause the same to rotate with the arbor, rotatable and vertically operating feed and pressure rollers, one of which rollers is adapted to contact with the cloth roll while it is being wound, a movable support for said rollers, detachable weights therefor, for the purpose set forth.

6. In a machine of the character described, a rotatable winding arbor adapted to support a paper tube about which cloth is wound into a roll and to form a core therefor, means for temporarily securing the tube to the ar-

bor, combined feed and pressure rollers, a movable support therefor, means for rotating said rollers, collars mounted on the winding arbor of larger diameter than the paper tube and adapted to support the weight of said rollers until the diameter of the cloth roll exceeds that of the said collars, for the purpose set forth.

7. In a machine of the character described, a rotatable cloth roll carrying arbor adapted to support the cloth roll while the same is being cut into spools, a cloth roll holding chuck longitudinally movable on said arbor and rotatably connected therewith, a rocker shaft, a support therefor, an arm mounted on said shaft, a circular cutter rotatably mounted on said arm rotating in the same direction as the roll, means for manually bringing the cutter into engagement with the cloth roll to sever spools therefrom, for the purpose set forth.

8. In a machine of the character described, a rotatable cloth roll carrying arbor, a cloth roll holding chuck longitudinally movable on said arbor and rotatably connected therewith, radially disposed sharp pointed pins projecting laterally from the front face of the chuck, radially operating slides in said front face, angularly disposed pins mounted in said slides, means for securing said slides, for the purpose set forth.

9. In a machine of the character described, a rotatable cloth roll carrying arbor, a cloth roll holding chuck therefor, pins 62^a projecting from the front face of the chuck, slides 63, 100 angularly disposed retaining pins 66 in said slides, means to secure said slides, slides 67 and 68, angular holding pins 69 and 70 adapted to be forced in the outer surface of a cloth roll and means for securing slides 67 and 68 105 for the purpose set forth.

10. In a machine of the character described, a rotatable cloth roll holding arbor, a cloth roll holding chuck, an arm, whose upper end is journaled in the chuck, and whose 110 lower end is longitudinally mounted on supports, means for feeding the chuck on the arbor comprising a metal toothed band anchored to said arm, rotatable supports therefor, a metal tension band, rotatable supports 115 therefor, means for connecting both bands together, and means for attaching the tension band to the arm of the chuck, means for tightening said tension band and toothed band, means for feeding said bands a predetermined distance, for the purpose set forth.

11. In a machine of the character described, a rotatable cloth roll holding arbor, a cloth roll holding chuck longitudinally movable on said arbor and rotatably connected 125 therewith, a rotatable cutter, a vertically movable support therefor, means for maintaining the proper cutting edge on the cutter and while said cutter is rotating in its support, for the purpose set forth.

12. In a machine of the character described, a rotatable cloth roll holding arbor, a cloth roll holding chuck longitudinally movable on said arbor and rotatably connected therewith, an arm, said chuck rotatably connected thereto, a support on which the arm is adapted to have a longitudinal movement, a toothed feed band anchored to said arm, rotatable pulleys on which said band is mounted, supports for said pulleys, a tension band, rotatable supports therefor, means for anchoring the feed and tension bands together, and means for anchoring the tension band to the said arm, and means for tightening said bands, a feed arm having a hub rotatably mounted on one of the feed band pulley supports, a pawl on said feed arm, a spacing arm rotatably secured to said feed arm, a stop pin between the feed and stop arms, so that, by means of said feed and stop arms and stop, the chuck is moved on the arbor a predetermined distance, for the purpose set forth.

13. In a machine of the character described, a rotatable arbor adapted to support a cloth roll, a chuck longitudinally movable on said arbor and rotatably connected thereto, means on said chuck for engaging one end of the cloth roll during the operation of cutting said cloth roll into spools, a rotatable cutter, a movable support therefor, means for mechanically feeding the chuck a predetermined distance to cut spools from the cloth roll of a predetermined width, a

gage or scale to prove the accuracy of the feeding movement of the chuck, for the purpose set forth.

14. In a machine of the character described, a rotatable arbor adapted to support a cloth roll to be cut into spools, a cloth roll holding chuck, a metal toothed feed band, means for connecting said band with the chuck and means for actuating said band, a tension band connected with said feed band to prevent its buckling, for the purpose set forth.

15. In a machine of the character described, a rotatable cloth roll carrying arbor, a cloth holding chuck longitudinally movable thereon, a circular cutter, and means for rotating said cutter and arbor in the same direction, for the purpose set forth.

16. In a machine of the character described, the combination with a rotatable cloth roll carrying arbor and a cloth roll holding chuck longitudinally movable thereon, of the arm 61 having its upper end journaled in the chuck and its lower end slidably mounted on two rods running parallel with said arbor, for the purpose set forth.

Signed at Bridgeport in the county of Fairfield and State of Connecticut this 22 day of Dec. A. D. 1906.
